UNITED STATES PATENT OFFICE.

ALICE A. ROTH, OF BUFFALO, NEW YORK.

RAILWAY-SWITCH.

SPECIFICATION forming part of Letters Patent No. 687,462, dated November 26, 1901.

Application filed August 19, 1901. Serial No. 72,469. (No model.)

To all whom it may concern:

Be it known that I, ALICE A. ROTH, a citizen of the United States, residing at Buffalo, in the county of Erie and State of New York, have invented new and useful Improvements 5 in Railway-Switches, of which the following is a specification.

This invention relates to that class of railway-switches which are designed more especially for use on street-railways and which are thrown by trip devices carried by the car and operated by the motorman without the necessity of leaving the platform or stopping the car.

15 The object of my invention is to provide an efficient switch of this character which is simple in construction, easy of operation, and not liable to get out of order.

In the accompanying drawings, consisting 20 of two sheets, Figure 1 is a sectional top plan view of a portion of a railway provided with my improved switch. Fig. 2 is a transverse vertical section in line 2 2, Fig. 1. Fig. 3 is a similar section in line 3 3, Fig. 1. Fig. 4 is 25 a horizontal section in line 4 4, Fig. 3. Fig. 5 is a fragmentary sectional elevation of a railway-car, showing the construction and arrangement of one of the trip-levers. Fig. 6 is a sectional top plan view of a modified 30 construction of the switch. Fig. 7 is a top plan view of the switch-casing with its top removed to expose the switch-operating mechanism. Fig. 8 is a transverse vertical section in line 8 8, Fig. 6.

35 Like letters of reference refer to like parts in the several figures.

A A' represent the rails of the main track, B B' those of the siding or branch track, and B² the usual guard-rail arranged adjacent to 40 the main rail A.

C represents a pivoted switch-tongue located at the inner side of the curve and having its free end arranged between the adjoining portions of the guard-rail B² and the side rail B in the usual manner. The adjacent 45 portions of the side rail B and guard-rail B² are offset or recessed, as shown at d, Fig. 1, to receive the free end of the switch-tongue in the customary manner. As shown in Figs. 50 1, 2, and 3, the switch-tongue is supported upon the horizontal top plate of a box or platform e, placed between the adjacent por-

tions of the main rail A, side rail B, and guard-rail B².

E E' are horizontally - swinging shifting 55 arms or levers arranged on opposite sides of the main and guard rails A B² and adapted to engage against the sides of the switch-tongue C for throwing the same into one or the other position. In the construction shown 60 in the drawings these shifting-arms are secured at one end to vertical pivots e, located at that side of the switch toward which the free end of the switch-tongue faces. As shown in Fig. 3, the pivots e are journaled 65 in bearings arranged in suitable casings F, which are placed below the switch flush with the surface of the pavement and which inclose parts of the switch-operating devices.

The shifting-arms E E' are provided at their 70 free ends with heads or enlargements e', having projections or salient portions e² at their front or inner sides, which pass through notches or recesses g, formed in the top of the opposing side and guard rails B B², and 75 which are adapted to bear against opposite sides of the switch-tongue, preferably near its free end.

Both of the shifting-arms E E' are preferably held in their retracted position out of 80 contact with the switch-tongue by suitable retracting devices, such as return-springs H. These springs are fastened at their outer ends to the side walls of the casings F and at their 85 opposite ends to horizontal return-arms I, secured to the pivots e of the shifting-arms, so that the springs tend to swing these arms outwardly through the medium of the return-arms I. As shown in Fig. 3, these return-arms are arranged below the top of the casings F. 90

The rear or outer sides of the shifting-arms E E' are straight, and when the arms are in their retracted position their straight rear sides lie obliquely or at an angle to the main-track rails, as shown by full lines in Fig. 1. 95 In this position the shifting-arms extend across the path of the trip devices J, carried by the railway-car, so that upon lowering one of these trip devices it strikes the corresponding shifting-arm E or E', thereby swinging the latter inwardly to the dotted position shown in Fig. 1 and causing it to throw the switch-tongue accordingly. A separate trip device is provided for each shifting-arm, and these

devices may be of any suitable or well-known construction. The preferred devices shown in the drawings consist of upright foot-levers pivoted to the car-truck by transverse pivots *j* and having their lower ends arranged to run against the oblique rear sides of the shifting-arms *E E'* when the upper arms of the levers *J* are swung in a forward direction sufficiently for this purpose. The upper arms of these levers pass freely through longitudinal slots or openings *k*, formed in the car-platform. The upper arms of the trip-levers normally stand in a rearwardly-inclined position, as shown by full lines in Fig. 5, so that when the upper arms of the levers are swung forwardly for depressing their lower arms the upper arms assume a substantially vertical position, as shown by dotted lines in said figure, in which position the levers are unaffected by the vertical vibrations of the car-body. The trip-levers are returned to their inoperative position by suitable springs *l*.

m represents guide-rails arranged parallel with the main rails and having their outer vertical sides in line with the rear sides of the shifting-arms *E E'*, so that upon lowering one of the trip-levers *J* it runs along the outer side of the adjacent guide-rail and thence along the rear side of the shifting-arm. These guide-rails extend forwardly some distance beyond the pivots of the shifting-arms in order to cause the trip-levers to engage the arms at a distance from their fulcrums for obtaining a more favorable leverage upon the same. As shown in Fig. 1, the rear sides of the shifting-arms are recessed to receive the adjacent portions of the guide-rails *m*.

The pivot-openings in the arms *E E'* preferably do not extend through the upper sides of the arms, but are formed by downwardly-opening sockets *e³* on the arms, which receive and cover the pivots *e*, as shown in Fig. 3, thereby preventing leakage of water through the pivot-openings, which would otherwise be liable to occur.

When the switch is set for the main track and it is desired to run the car upon the branch track, the motorman on approaching the switch lowers the outer or left-hand trip-lever *J* of the car. This lever now runs along the adjacent guide-rail *m* and the back of the corresponding shifting-arm *E* and swings the latter forwardly, causing it to throw the switch-tongue to the position shown by dotted lines in Fig. 1. If the switch is set for the branch track and the motorman desires to run the car along the main line in the direction of the arrow, Fig. 1, he lowers the inner or right-hand trip-lever *J*, whereupon this lever swings the inner shifting-arm *E'* toward the other shifting-arm *E* and throws the switch-tongue in the same direction, setting the same for the main track. When a car runs from the branch to the main track or approaches the switch on the main track in the direction contrary to that of the arrow in Fig. 1, the switch-tongue is deflected aside by the car-wheels in the

usual manner. The forward movement of either of the shifting-arms *E E'* causes the corresponding spring *H* to be strained, and as soon as the trip device of the car clears the shifting-arm the latter is retracted to its former position by the reaction of its spring. To insure the retraction of the shifting-arms *E E'* in case their springs *H* should become weak or inoperative, the head of each arm is preferably provided at its front edge with oblique faces or cams *n n'*, which recede in opposite directions from the salient central portion *e²* of the head, as shown in Fig. 1. If the head of one of the shifting-arms should project across the path of the car-wheels, the foremost wheel will strike and run along the adjacent cam-face *n* or *n'* of said head, according to the direction in which the car is running, and thereby deflect the shifting-arm aside, this deflecting action taking place whether the car approaches the switch in one or the other direction or runs from the main to the branch track, or vice versa.

The usual flanged heads of the rails are not wholly cut away in forming the recesses *g*; but the latter are only of sufficient depth to receive the shifting-levers *E*, so as to leave the lower portion of said head-flanges. These unremoved portions form supports or bridges upon which the flanges of the car-wheels run in passing over the recessed portions of the rails, thereby preventing jarring and pounding of the wheels at the breaks in the rails formed by said recesses.

In the modified construction of the switch shown in Figs. 6, 7, and 8 a single shifting-arm *E²* is employed for throwing the switch-tongue *C* in one direction, and the tongue is thrown in the opposite direction by a spring *H'*. In this case the tongue is secured to a rocking pivot *e⁴*, which is provided below the top of the casing *F'* with an arm *o*, and the spring *H'* is attached at its ends to this arm and the casing, as shown in Fig. 7, so that the spring holds the switch-tongue in position for directing the car along the main track. This construction requires but a single trip device *J* on the car. The shifting-arm *E²* in this case bears against the outer side of the switch-tongue and passes through a notch *g'* of the adjacent rail, as in the first-described construction. In the use of this modified switch the same is normally set for the main track, and when it is desired to run upon the side or branch track the motorman depresses the trip device on approaching the switch, causing the shifting-arm *E²* to be swung forwardly and throwing the switch-tongue to the position shown by dotted lines in Fig. 6. In this construction the shifting-arm must be of sufficient length to allow the front wheel of the rear car-truck to engage the point of the tongue before the rear wheel of the front truck clears the tongue.

I claim as my invention—

1. In a switch-operating mechanism, the combination with main and side tracks and

a movable switch-tongue, of a rigid horizontally-swinging shifting-lever arranged lengthwise of the switch-tongue and having its pivot located beyond the point of the tongue, the 5 rear side of the shifting-lever lying normally in an oblique position with reference to the main track and its free front end being arranged to bear against the side of the tongue near its point, and means for effecting the 10 return stroke of the shifting-lever, substantially as set forth.

2. In a switch-operating mechanism, the combination with a track-rail provided in the upper surface of its head with a recess extending only partly into the head, for leaving a bridge or support for the wheel-flanges opposite said recess, of a movable switch-tongue arranged adjacent to said recess, and a horizontally-swinging shifting-lever arranged 15 to pass through said recess and engage against the switch-tongue, substantially as set forth.

3. In a switch-operating mechanism, the combination with main and side tracks and 20 a switch-tongue, of opposing horizontal shifting-levers arranged lengthwise on opposite sides of the tongue and each provided at its front edge with a retracting-cam arranged to be engaged by a trip device on the car, the 25 adjacent track-rails having recesses for the passage of said shifting-levers, and return-springs operating upon said shifting-levers, substantially as set forth.

4. In a railway-switch, the combination of a main and a side track, a pivoted switch-tongue, horizontal shifting arms or levers arranged to bear against opposite sides of the switch-tongue and each mounted upon a rocking pivot, return-arms secured to said pivots, and retracting-springs connected with said 35 return-arms, substantially as set forth.

5. In a railway-switch, the combination of a main and a side track, a movable switch-tongue, a pivoted horizontal shifting-arm arranged to bear against the side of the switch-tongue, and a guide-rail arranged in line with the rear side of said shifting-arm and extending 40 forwardly beyond its fulcrum, substantially as set forth.

6. The combination of a railway having a 45 movable switch-tongue, a car having an aperture in its platform, and a trip-lever mounted upon one of the car-trucks and adapted to engage said switch-tongue, the upper or actuating arm of said lever passing freely 50 through the aperture of the car-platform and being arranged to stand normally in a rearwardly-inclined position, substantially as set forth.

Witness my hand this 14th day of August, 60 1901.
